UNITED STATES PATENT OFFICE.

JAMES S. DOYLE, OF MOUNT VERNON, AND FRANK HEDLEY, OF YONKERS, NEW YORK.

LOAD-REGULATED GOVERNING DEVICE FOR FLUID-PRESSURE.

1,096,493.

Specification of Letters Patent.

Patented May 12, 1914.

Application filed August 23, 1912. Serial No. 716,657.

To all whom it may concern:

Be it known that we, JAMES S. DOYLE and FRANK HEDLEY, both citizens of the United States, residing, respectively, at Mount Vernon and Yonkers, in the county of Westchester and State of New York, have invented a certain new and useful Improvement in Load-Regulated Governing Devices for Fluid-Pressure, of which the following 10 is a specification.

This invention relates in general to apparatus for regulating the fluid pressure for braking purposes upon railway cars according to the weight of the load upon the car, 15 and is more particularly designed for use in connection with electrically propelled vehicles in which the air pressure for the brake system is supplied to a main reservoir by means of an electric motor-driven pump, the 20 motor of which is controlled by an electric pump governor according to the pressure in the reservoir.

It is well known that a higher braking power is required to control a heavily loaded 25 car than a light or empty car, also that a much greater braking pressure may be applied to the shoes of a loaded car than to a light car without danger of sliding the wheels. It is therefore important to be able 30 to vary the maximum braking pressure according to the weight of the load in order that the braking apparatus shall operate efficiently and satisfactory in actual service.

The principal object of our invention is 35 therefore to provide means for automatically varying the maximum degree of pressure stored for braking purposes, in accordance with the weight of the load on the car, and as a preferred means for this purpose we 40 may employ a device governed by the weight of the load on the car for regulating the pump governor, whereby the maximum degree of reservoir pressure at which the governor cuts out the pump will be increased 45 as the load is increased.

The single figure of the accompanying drawing illustrates diagrammatically an apparatus embodying our improvement.

According to the construction shown, our 50 improvement is applied in connection with

an electric pump governor of the type commercially known as the Westinghouse G type, in which a magnet coil is employed for assisting the spring to hold the switch closed and thereby require the reservoir pressure 55 to rise to a point sufficient to overcome both the spring and the magnetic pull of the coil in order to open the switch and cut out the pump. Current is supplied to the motor-driven pump, 20, through leads, 4, connected to the switch terminal points, 8, one of said leads containing the coil, 2, of the governor. The switch terminal points are adapted to be joined by the connecting bar, 9, when the switch is closed, at which time 60 current flows through leads, 4, switch terminal points and coil, 2, to the motor-driven pump, 20, which operates to compress air into the reservoir, 1. As the pressure accumulates in the reservoir, it is also admitted to cylinder, 6, where it acts upon the piston, 5, and rod, 7, of the governor and tends to open the switch against the pressure of the adjustable spring, 12, and the magnetic pull exerted by the coil, 2. When 65 the air pressure has increased to a point sufficient to overcome the spring and the pull of the magnet, it pushes the switch bar away from the switch terminals, and the instant the circuit, which includes the coil, 2, 70 is broken, the magnetic pull, of course, ceases, so that the governor piston and rod move with a quick positive movement to the cut out position at the end of the stroke of the piston. The spring, 12, is adjusted for 75 the cutting in pressure, and when the reservoir pressure has reduced to the degree for which the spring is set, it operates to move the switch bar to its closed position, the magnet, 2, being energized the instant that the 80 contact is made. The construction, as thus far described, relates to this standard form of electric pump governor.

According to our improvement, any means controlled by the weight of the load on the 95 car may be employed for regulating the action of the pump governor, and the pressure in the reservoir. As a preferred construction we have shown an additional coil, 3, for the governor, included in a circuit, 14, and act- 100

ing in a manner similar to the coil, 2, that is, to exert a magnetic pull upon the armature or switch bar, 9, and assist in holding the same closed in order to thereby raise the 5 cutting out point and increase the maximum pressure carried in the reservoir. The current for the coil, 3, may be taken from any convenient source, as for instance from a lead, 13, tapped from the line, and the 10 strength of this current and the corresponding magnetic pull in coil, 3, may be controlled by a resistance, R, inserted in this circuit, 14. This circuit may also be provided with contact terminals, 10, adapted to 15 be connected by a bar, 11, carried on the switch arm, 9, when in closed position, and disconnected in the open position in order not to affect the cutting in point of the governor.

20 Any suitable or preferred form of switch mechanism operated automatically by the weight of the load on the car may be employed for varying the resistance in circuit, 14, and thereby regulate the governor, and 25 for this purpose we have indicated a switch arm, 15, fulcrumed at 16 to some fixed part of the car or truck, such as transom, 19, and connected at one end, 17, to a depressible part, such as the bolster, 18, supported on 30 the car springs. When the car is empty, the arm, 15, occupies the position shown in which all of the resistance, R, is included in the circuit, 14, so that there is little or no current passing through the coil, 3, and consequently there is no additional magnetic 35 pull or effect upon the governor, which then operates in the usual way to cut out the pump at desired maximum degree of pressure for which the governor is adjusted.

40 When, however, the load is increased upon the car, the car springs are further depressed and the switch arm, 15, swings over the contact points to a position in which a certain amount of resistance is cut out, 45 thereby increasing the current in circuit, 14, and the strength of the magnetic pull exerted by the coil, 3. This operates to raise the cutting out point of the governor and increases the maximum pressure stored in 50 the reservoir.

While we have shown our improvement applied in connection with a particular form of pump governor, it will be evident that it is not restricted to this form, but may also be employed with any other suitable or preferred governor construction.

It will now be apparent that by means of our improvement, the maximum degree of air pressure in the reservoir will be regulated 60 according to the weight of the load on the car, increasing as the load increases, and diminishing as the load is reduced, thereby affording at all times a suitable and ade-

quate braking pressure for controlling the car in an efficient and satisfactory manner. 65

Having now described our invention, what we claim as new and desire to secure by Letters Patent is:

1. The combination on a car, of a pump and reservoir for storing air under pressure, 70 and a pump governor controlled by the weight of the load on the car.

2. The combination on a car, of a pump governor for controlling the degree of fluid pressure stored for braking purposes, and 75 means controlled by the weight of the load on the car for regulating the governor to vary the maximum degree of pressure stored.

3. In a governing device for fluid pressure pumps, the combination with a switch 80 for controlling the supply of current to the pump, of a piston subject to the fluid pressure for operating said switch, and means controlled by the weight of the load on the car for opposing the action of the fluid pressure on the piston. 85

4. In a governing device for fluid pressure pumps, the combination with a switch operated by the opposing pressures of the compressed fluid and an adjustable spring, 90 and means controlled by the weight of the load on the car for assisting the spring in holding the switch closed.

5. In a governing device for fluid pressure pumps, the combination with a switch 95 governed by the fluid pressure for controlling the action of the pump, a magnet coil tending to hold said switch closed, and means controlled by the weight of the load on the car for varying the current in said 100 magnet.

6. In a governing device for fluid pressure pumps, the combination with a switch governed by the fluid pressure for controlling the action of the pump, a magnet coil 105 tending to hold said switch closed, and means controlled by the weight of the load on the car for varying the resistance in the circuit of said magnet.

7. In a governing device for fluid pressure pumps, the combination of a switch for controlling the action of the pump, a piston subject to the opposing pressures of the pump and an adjustable spring for operating the switch, a magnet coil tending to assist the spring in holding the switch closed, 115 mechanism controlled by the weight of the load on the car for varying the resistance in the circuit of said coil, and means operated by the opening movement of the governor switch for also opening the circuit of said coil.

8. In a governing device for fluid pressure pumps, the combination of a switch for controlling the action of the pump, a piston 125 subject to the opposing pressures of the

pump and an adjustable spring for operating the switch, a magnet coil included in the pump circuit and tending to hold the switch closed, another magnet coil also tending to hold the switch closed, and mechanism controlled by the weight of the load on the car for varying the strength of the latter magnet.

In testimony whereof we have hereunto set our hands.

JAMES S. DOYLE.
FRANK HEDLEY.
